Attorney, Agent, or Firm—Edward E. Roberts[57] **CLAIM**

The ornamental design for a axle and base frame of collapsible baby jogging stroller, as shown.

DESCRIPTION

FIG. 1 is a perspective view of a collapsible baby jogging stroller showing my new design;

FIG. 2 is a front elevational view thereof;

FIG. 3 is a back elevational view thereof;

FIG. 4 is a top view thereof; and

FIG. 5 is a side elevational view thereof; and,

FIG. 6 is a sectional view showing the ovate configuration of the tubes designated.

The broken lines shown in FIGS. 1 through 5 are for illustrative purposes only and form no part of the claimed design.
